US00D939635S

(12) **United States Design Patent** (10) Patent No.: **US D939,635 S**
Chen (45) Date of Patent: **** Dec. 28, 2021**

(54) **STRESS REDUCTION SQUEEZE TOY**

(71) Applicant: **Yashan Chen**, Putian (CN)

(72) Inventor: **Yashan Chen**, Putian (CN)

(**) Term: **15 Years**

(21) Appl. No.: **29/771,970**

(22) Filed: **Feb. 26, 2021**

(51) LOC (13) Cl. **21-01**

(52) U.S. Cl.
